INVENTOR

FREDERICK STIFFLER

BY Thomas L. Ryan

ATTORNEY.

UNITED STATES PATENT OFFICE.

FREDERICK STIFFLER, OF MUNCIE, INDIANA.

SLED.

1,404,244.

Specification of Letters Patent. Patented Jan. 24, 1922.

Application filed December 23, 1920. Serial No. 432,728.

To all whom it may concern:

Be it known that I, FREDERICK STIFFLER, a citizen of the United States, residing at Muncie, in the county of Delaware and State 5 of Indiana, have invented certain new and useful Improvements in Sleds, of which the following is a specification.

This invention relates to improvements in sleds of that class or type intended to be 10 propelled by the rider.

Objects of this invention are to provide simple and efficient means connected to and constituting a part of the sled construction by which exhilarating and healthful exercise for the rider is afforded and at the same time the sled may be propelled. More specific purposes are to provide a construction, combination and arrangement of parts that is economical of construction, durable, light 20 in weight, and not liable to get out of order or repair.

In the accompanying illustration is shown the preferred form of embodiment of my invention, it being understood that minor 25 changes may be made in the general construction and arrangement and proportioning of the several combined parts, within the scope of the invention as defined by the appended claim, without departing from the 30 nature or spirit of the invention or sacrificing any of its advantages.

My invention is illustrated in the accompanying drawings, described in the following specification, and is defined in the appended claim. The several parts of the invention, as they appear in the different views in the drawings, are identified by suitable characters of reference.

Figure 1 is a central longitudinal sectional view of my improved sled, taken on the line 1—1 in Figure 2, the front and rear portions being shown in elevation.

Figure 2 is a top plan view of the sled, a portion of the top board being broken away.

The runners 1 and 1^a may be made of steel sheet metal of suitable gauge of thickness, and of the form shown, and they are retained at properly spaced distance apart by suitable transverse brace members 2, 3, 4 and 5. At a location suitably distant from the forward end of the runners they are divided vertically, the forward portions thereof being designated pilot runners 6 and 6^a. These pilot runners are retained at 55 spaced distance apart by a cross bar 7 and

upon which bar there are secured foot rests 8 and 8.

Each of the pilot runners has its vertical edge 6^b beveled, as shown in Figure 2, and they are connected to the main runners 1 and 1^a by resilient connectors. These connectors, designated as springs may consist of flat bar springs 9 and 9 arranged longitudinally and connected to the runners as shown. While these springs normally retain the sections of runners in alignment, the pilot runner may be urged in a direction slightly to the right or to the left, so that the direction of movement of the sled may be accordingly varied by the pressure of the 70 rider's feet at the foot rests. 10 designates a suitable stay rod to maintain the points of the pilot runners at spaced distance apart.

Arranged between the runners 1 and 1^a is a driven member which consists of a transverse bar 11 having shoulders 11^a at the spindles 11^b. The integrally formed arms 11^c have the shoulders 11^d which bear against the inner side of the runner, and the studs 11^e that engage in the slot 12 of the runner. 80 Lugs 13 that are formed integrally near each end of the bar 11, constitute rests against which the grip bars 14 are normally retained by a leaf spring 15 that is secured to the arm 11^c. By the construction described it is observed that the grip bars occupy oppositely disposed positions one being on the inside of each of the runners 1 and 1^a. Each of the grip bars is made of metal, and has its upper end loosely retained on 90 the spindle 11^b of the driven bar 11; its lower end 14^a being toothed as shown in Figure 2. Projecting from the side of the lower portion of the grip bar is a stud 14^b whose function will be presently referred to. 95

16 designates a drive bar provided at its upper end with handles 16^a. The lower end of this drive bar is connected to a support rod 17 which has its ends journaled in the runners 1 and 1^a, as shown plainly in Figure 2. At a suitable location on the drive bar 16, the forward end of a connecting link member 18 is loosely connected by a bearing pin 19. The lower end of the connecting link is journaled on the driven bar 11. 100

The suitable top board 20 of the sled is properly secured to the members 2, 3, 4 and 5, and may be of width to cover the top edges of the runners. At the inner surface near the lower edge of each of the runners, 110

is provided a lift cam 21, so located with reference to the slot 12 that when the grip bar 14 has been carried to position beyond its normal rearward travel, in the propelling of the sled, the studs 14^b engage the surface of the said cam and the grip bar is lifted to a height sufficient to disengage the points 14^a of the grip bar, from the snow surface.

10 The utility of my invention, and the mode of use, is apparent from the foregoing description, and a reading of the drawings. Propulsion of the sled on horizontal or inclining grades is practicable; and at the 15 same time the use of the sled in drifting or coasting is equally effective.

The rider may be seated at natural position on the top board, grasping the handles 16^a and having his feet on the foot rests 8 20 and 8. With the swinging forwardly of the drive bar 16, the driven bar 11 is moved to the limit of its forward stroke, the points of the grip bars being in direct or gripping contact with the snow surface. By a rearward pull then of the drive bar, the sled is caused to be moved forwardly. A forward movement then by the rider of the drive bar 16 carries the driven bar 11 to the limit of 25 its forward stroke; the points of the grip bars being at contact with the snow surface, a rearward pull of the drive bar causes the sled to be again moved forwardly. The repetition by the rider, of the reciprocating movement of the drive bar, causes a succession of impulses to be imparted to the sled, thus maintaining the forward movement of

the sled. The range of the normal forward and rearward travel of the drive bar is shown by the dotted lines. In coasting, the rider may retract the drive bar to the extreme rearward position, the studs 14^b of the grip bars rising on the cams 21 thus being disengaged from the snow-surface.

It is contemplated that the several parts of the invention, while of proper strength, 45 may be light in weight and economical of construction and assembly. To fold down the drive bar on the sled, the pin 19 is removed, enabling the drive bar to be folded down, and the connecting link to be 50 dropped down. With these parts so folded down it is practical to arrange the sleds in quality order for the purposes of shipments in bulk as an article of manufacture.

Claim: 55
A sled, comprising parallel runners each having a slot in its upper portion, a transverse driven bar having its ends to reside in the said slots thiere being a lug near the ends of the driven bar, a grip bar loosely retained near each end of the driven bar and to rest against said lug, a spring to press against said grip bar, a drive bar capable of being reciprocated, a connecting link between the drive bar and the driven bar, and cams carried by the runners so arranged that when the driven bar is at retracted positions the grip bars will have been lifted from the contact with the snow surface.

In testimony whereof I affix my signature.

FREDERICK STIFFLER.
